A. FODOR.
PROCESS OF REPRODUCING ARTICLES IN METAL.
APPLICATION FILED APR. 17, 1917.

Patented Mar. 4, 1919.

A. Fodor Inventor
By his Attorney Hugo Wock

UNITED STATES PATENT OFFICE.

ANTAL FODOR, OF NEW YORK, N. Y., ASSIGNOR TO DYMALKON METALS CORPORATION,
OF NEW YORK, N. Y., A CORPORATION OF NEW YORK.

PROCESS OF REPRODUCING ARTICLES IN METAL.

1,296,498.

Specification of Letters Patent.

Patented Mar. 4, 1919.

Application filed April 17, 1917 Serial No. 162,797.

To all whom it may concern:

Be it known that I, ANTAL FODOR, a subject of the Emperor of Austria-Hungary, residing at New York, in the county of New York and State of New York, have invented certain new and useful Improvements in Processes for Reproducing Articles in Metal, of which the following is a specification.

10 This invention relates to a new process for reproducing articles in metal such as statues, busts, signs and figures of all kinds.

An object of this invention is the production of artistic figures of metal in an 15 economical fashion and which will be faithful to the original reproduced.

Another object of my invention is to substitute for the present costly process of casting in metals a process which will be time 20 and labor saving and which will permit the sale of such reproductions nearly at the price of ordinary plaster cast figures.

The essential features of our process are the making of a negative mold from an 25 original in one or more parts, the reproduction of a positive copy in a thin sheet from said negative mold in one or more parts, and the subsequent treatment of the positive copy so produced as will be hereinafter 30 more fully described.

In the drawings, Figure 1 is a sectional view in two parts of a mold of a head which is a negative matrix of the head to be reproduced.

35 Fig. 2 is a sectional view similar to Fig. 1 but showing the two parts joined.

Fig. 3 is a sectional view showing the same head with the negative matrix removed and the same electroplated on its exterior surface, and

40 Fig. 4 is a sectional view of the head with a portion of the material thereon removed and electroplated on its interior surface.

1 and 2 indicates a negative mold made 45 in two parts. On the inner surface of parts 1 and 2 a layer of thin metal is deposited preferably by means of spraying and for convenience in making this initial positive layer, we use a comparatively low fusible 50 composition made of lead, tin and antimony.

55 Into the parts 3 and 4 respectively, an insulating material such as asphalt or paraffin is now poured as shown at 5 and 6 in the drawing. The parts 1 and 2 are then joined and to cement the same more firmly together

a portion of the same insulating composition indicated at 7 is poured upon 5 and 6. When the composition has cooled, the negative molds 1 and 2 can be stripped from the surfaces 3 and 4 leaving the positive copy 60 of the article to be reproduced in one piece as shown in Fig. 3. As the surface 3 is not made of a durable material, same is then subjected to an electroplating bath to furnish thereon an adherent surface of copper 65 or other material which will withstand wear, said surface being marked 10 on the drawings. We have found it convenient in practice to polish off the seam 8 where the parts 3 and 4 are joined and afterward to furnish 70 this seam with an electrically conductive surface as of graphite, before electroplating. By electroplating the entire piece, a homogeneous surface is obtained on same which can be very thin so as not to distort the 75 details of the object to be reproduced inasmuch as the positive layers 3 and 4 are already of metal. After the plating is completed, the object may be put in hot water to melt and remove the insulating material 80 5, 6 and 7 which flows out through the hole 9.

In order to increase the weight or solidity of the figure, it can again be filled 85 through the hole 9 with a metallic or non-metallic composition shown at 11 in Fig. 4.

By the above process we are enabled to reproduce metallic or non-metallic articles cheaply and with great fidelity to the originals and in a durable non-breakable form. 90

What I claim is:

1. A method of making metallic reproductions by preparing positive metal copies from negative matrices in several parts and joining said parts by a material of low 95 fusibility.

2. A method of making metallic reproductions by preparing positive metal copies from negative matrices in several parts and joining said parts by a material of low fusibility and afterward electroplating said parts. 100

3. A process of making metallic reproductions by producing positive copies from negative matrices, joining said copies by 105 material of low fusibility, electroplating said copies and afterward reinforcing said electroplated object.

4. A method of making metallic reproductions by preparing a negative matrix in 110

several parts, preparing positive copies therefrom, joining said positive copies and electroplating said positive copies so as to produce a single piece.

5. A method of making metallic reproductions by making a negative matrix, producing a positive copy in a thin metallic sheet upon said matrix by spraying, reinforcing said positive copy with an insulating material of low fusibility, electroplating said positive copy, removing said insulating material.
10. A method of making metallic reproductions by making a negative matrix, producing a positive copy in a thin metallic sheet upon said matrix by spraying, reinforcing said positive copy with an insulating material of low fusibility, electroplating said positive copy, removing said insulating material.

6. A method of making metallic repro-

ductions by making a negative matrix, producing a positive copy in a thin metallic sheet upon said matrix by spraying, reinforcing said positive copy with an insulating material of low fusibility, electroplating said positive copy, removing said insulating material and reinforcing said positive copy after said insulating material has been removed.

In testimony whereof I hereunto affix my signature.

ANTAL FODOR.
